UNITED STATES PATENT OFFICE

2,434,216

TRANSFER MECHANISM FOR PLURAL COMPARTMENT CONCRETE MIXING DRUMS

Andrew McMillan, Milwaukee, Wis., assignor to
Chain Belt Company, Milwaukee, Wis., a corporation of Wisconsin

Application December 4, 1944, Serial No. 566,491

3 Claims. (Cl. 259—175)

1

The invention relates to concrete mixing apparatus, more especially the kind employing a plural compartment rotatable mixing drum, and represents a further development of the apparatus of this character disclosed in prior U. S. Patents No. 2,131,682 granted September 27, 1938, and No. 2,135,436 granted November 1, 1938, on applications filed by Charles F. Ball. More particularly, the invention relates to the mechanism for controlling the transfer of the concrete mixture from one compartment of the drum to the other.

For purposes of disclosure one form of the invention has been illustrated in the accompanying drawings forming a part of this specification, in which like reference characters designate like parts in all the views, and in which:

Figure 1 is a longitudinal sectional-elevational view of a two-compartment mixing drum for concrete mixers, in which transfer mechanism constructed and arranged in accordance with the invention has been incorporated;

Fig. 2 is an enlarged transverse sectional view on the plane indicated by the line 2—2 of Fig. 1, looking in the direction of the arrows;

Fig. 3 is a vertical sectional view on the plane indicated by the line 3—3 of Fig. 2, looking in the direction of the arrows, the parts being shown in the open or transfer positions;

Fig. 4 is a horizontal sectional-plan view, on the plane indicated by the line 4—4 of Fig. 1, looking down; and

Fig. 5 is a partial transverse sectional view, on a reduced scale, on the plane indicated by the line 5—5 of Fig. 3.

The drum 10 illustrated in Fig. 1 is of a type widely used in concrete mixers of the paving and other types and its heads 11 and 12 are respectively provided with the charging opening 13 and the discharging opening 14, with the former of which is associated a charging chute 15 fixedly carried by the framework of the machine and adapted to receive the aggregates and cement from the charging skip, not shown, for charging into the drum through the said opening 13. A discharge chute 16 is pivotally mounted at 17 adjacent the discharge opening 14 for swinging movements from the discharge position shown to an oppositely inclined non-discharge position outside the drum, such movements being effected by means of a power discharge mechanism 18 of well known form through appropriate linkage 19.

Medially between its ends the drum is provided with a transverse partition structure 21 dividing it into two chambers or compartments 22 and 23 in each of which are drum-carried mixing blades of known form, some of those in compartment 22 being indicated at 24. As will be readily understood by those skilled in the art, a batch of concrete constituents is introduced into the primary

2

compartment 22, there mixed for a portion only of the required mixing period, then transferred to secondary compartment 23, and while its mixing is being completed therein a fresh batch of materials is fed into and preliminarily mixed in compartment 22. Thus, two batches are handled simultaneously and a material increase in the output of the machine attained as compared to that of a single compartment drum.

10 The partition structure 21 comprises an annulus 25 disposed substantially perpendicular to the axis of the drum and having its outer peripheral portion secured to the drum wall, as by an angle bracket 26. To its inner periphery is 15 welded or otherwise secured a frusto-conical annulus 27 which also extends to the drum wall, as shown in Fig. 1. The interior of the annulus 27 is provided with a truncated coniform liner 28 which, as best shown in Fig. 3, projects through 20 the opening in the annular structure 25, 27 and into the chamber 23. Upon the projecting portion of the liner 28 is seated a frusto-conical annulus 29 provided with an outer peripheral flange 30 which is secured by bolts 31 to the annulus 25. The inner periphery of the annulus 29 carries 25 a seating ring 32, surrounding the transfer opening 33 of the partition structure, provided by the openings of the annuli 28 and 29.

25 Mounted upon the annulus 29 and extending 30 into the chamber 23 is a spider structure 35 comprising a plurality of circumferentially spaced arms 36, one end of each of which is attached as by a bolt 31 to an angle bracket 38 welded or otherwise secured to the annulus 29. Each arm 35 is curved as at 39 to extend radially inward toward the axis of the drum, and the inner ends are secured as by bolts 40 to a ring 41. Each arm also has a spline plate 42 adjustably secured to its inner end by bolts 43. The inner ends of the 40 spline plates 42 are slidably received in grooves or keyways 44 provided in members 45 rigidly carried by a sleeve 46 which in turn is rigidly mounted upon one end portion of a shaft 47 extending axially of the drum. Adjacent the 45 sleeve 46 and within the spider structure 35, the said shaft 47 carries a transfer-control door 48 which as best shown in Fig. 3, comprises a dished disc 49 mounted upon the said shaft by a ball and socket joint structure 50 and provided 50 at its outer periphery with a yieldable packing ring 51 adapted for sealing engagement with the seating ring 32. The joint 50 is enclosed within a flexible housing 52 whereby it is protected against the concrete mixture while at the same 55 time universal movement of the door 48 is permitted to enable it to fully seat the packing 51 against the ring 32.

The shaft 47 extends forwardly, i. e. toward the charging end of the machine, through the 60 transfer opening 33 and into the chamber 22

where its other end is rotatably connected to a fork or yoke structure 55, best shown in Fig. 4. As will be understood from this figure, the spaced arms 56 of this structure are rigidly secured to 57 and by a transverse brace member 58 to a sleeve 59 which is provided with bearings 60 in which the shaft 47 is journaled. Relative endwise movement between the shaft and the fork structure in one direction is prevented by a split washer 62 mounted in a groove 63 in the shaft 10 and abutting a thrust bearing 64. A cap 65 covers the end of the shaft 47 and through engagement therewith and/or with the washer 62, prevents endwise movement in the opposite direction. Thus, reciprocating movements may be imparted to the shaft by the fork structure to move the transfer door 48 to and from engagement with the seating ring 32, while at the same time the shaft and door are free to rotate with the drum and partition structure.

As will be clear from Fig. 1, the arms 56 of the fork structure extend through the charging opening 13 of the drum, one to either side of the charging chute 15, and at their forward ends they are connected to a lever 66 which is actuated through a link 66 by a power mechanism 67, similar to the mechanism 18 which actuates the discharge chute 16. The mechanisms 18 and 67, which may be of the general type disclosed in prior U. S. Patent No. 1,415,411 to Samuel Shafer, Jr., are operated in appropriately timed relation whereby the discharge chute 16 is moved to the discharging position of Fig. 1 only when the transfer door is closed, and conversely the said door is moved to the open position of Fig. 3 only when the chute 16 is in its non-discharging position.

The spider structure 35, being rigidly mounted on the partition structure 21 and being located in the second compartment 23 of the drum, provides in the members 42, 45 a sturdy outboard spline bearing for the extreme end portion of the shaft 47; which bearing, being behind the door 48 is completely out of the path of the concrete mixture during transfer from one compartment to the other and thus offers no impediment whatever to such transfer. Furthermore, the arms 36 of the spider structure 35 are preferably disposed circumferentially intermediate the discharge portions 24 of the blades 24 of compartment 22 (which blades, as is well known, move the mixture to and through the transfer opening 33) and therefore the said arms offer a minimum of interference to the transfer.

To facilitate and speed up the transfer of the mixture from the compartment 22 through the opening 33 into compartment 23, the shaft 47 may be provided with a plurality of longitudinally extending vanes or fins 70 which are welded or otherwise rigidly secured to the shaft for rotation and longitudinal movement therewith. These fins are so disposed upon the shaft that in the normal position of the parts they are retracted from the transfer opening 33, as shown in Fig. 1, so as not to interfere with the mixing action of the blades 24 and transfer scoops 24'. However, when the shaft 47 is moved toward the left to open the door 48 for transfer of the mixture from one compartment to the other, the vanes 70 move with the said shaft to positions within or immediately adjacent the opening 33, as shown in Fig. 3, where they may deflect the mixture as it is discharged by the scoops 24' and translate its rotary motion into longitudinal motion thereby facilitating its passage through the said opening.

While one form of the invention has been illustrated and described for purposes of disclosure, it is obvious that those skilled in the art may vary the details of construction as well as the precise arrangement of parts without departing from the spirit of the invention, and therefore it is not wished to be limited to the above disclosure except as may be required by the claims.

What is claimed is:

1. In a concrete mixing drum, having a transverse partition dividing it into primary and secondary mixing compartments, which partition is provided with a transfer opening for the mixture, said drum also having rotatable elements in said primary compartment for moving the mixture toward said opening; a door mounted for reciprocation axially of the opening whereby to control transfer of mixture therethrough; and members disposed adjacent the opening and axially reciprocatable with the door from a position removed from the opening when the door is closed, to a position adjacent the opening when the door is open, whereby in the latter position they may deflect mixture from said rotatable elements through the opening.
2. In a concrete mixing drum, having a transverse partition dividing it into primary and secondary mixing compartments, which partition is provided with a transfer opening for the mixture, said drum also having rotatable elements in said primary compartment for moving the mixture toward said opening; a reciprocatable shaft mounted axially of the opening; a door carried by the shaft for movements to and from the opening whereby to control transfer of the mixture therethrough; and fins carried by the shaft for movement from a position removed from the opening when the door is closed, to a position adjacent the opening when the door is open, whereby in the latter position they may deflect mixture from said rotatable elements through the opening.
3. In a concrete mixing drum, having a transverse partition dividing it into primary and secondary mixing compartments, which partition is provided with a transfer opening for the mixture, said drum also having rotatable elements in said primary compartment for moving the mixture toward said opening; a reciprocatable shaft mounted axially of the opening; a door carried by said shaft within the secondary compartment for movements to and from the opening whereby to control transfer of the mixture through the latter; and fins carried by the shaft within the primary compartment for movement simultaneously with the door from a position removed from the opening when the door is closed, to a position adjacent the opening when the door is open, whereby in the latter position they may translate motion of the mixture discharged by said rotatable elements and facilitate its passage through the opening.

ANDREW McMILLAN.
